(57) **CLAIM**

The ornamental design for a bag hanger, as shown and described.

DESCRIPTION

FIG. 1 is a perspective view of a bag hanger; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; FIG. 7 is a bottom plan view thereof; FIG. 8 is a front view thereof; and, FIG. 9 is a cross-sectional view thereof, taken along lines 9-9 indicated in FIG. 8.

The broken lines shown represent unclaimed subject matter and form no part of the claimed design.

The long dash-short dash lines shown in FIG. 8 represent the section from which the cross-sectional view is taken and form no part of the claimed design.
